(57) **CLAIM**

The ornamental design for a set of building blocks as shown and described.

DESCRIPTION

FIG. 1 is a front elevational view of a first piece of a first building block of a set of building blocks, shown separately for ease of illustration;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is a front elevational view of a second piece of the first building block of the set of building blocks, shown separately for ease of illustration;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof;

FIG. 14 is a perspective view thereof;

FIG. 15 is a front elevational view of a second building block of the set of building blocks, shown separately for ease of illustration;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof;

FIG. 21 is a perspective view thereof;

FIG. 22 is a front elevational view of a first piece of a third building block of the set of building blocks, shown separately for ease of illustration;

FIG. 23 is a rear elevational view thereof;

FIG. 24 is a left side elevational view thereof;

FIG. 25 is a right side elevational view thereof;

FIG. 26 is a top plan view thereof;

FIG. 27 is a bottom plan view thereof;

FIG. 28 is a perspective view thereof;

(Continued)

FIG. 29 is a front elevational view of a second piece of the third building block of the set of building blocks, shown separately for ease of illustration;
FIG. 30 is a rear elevational view thereof;
FIG. 31 is a left side elevational view thereof;
FIG. 32 is a right side elevational view thereof;
FIG. 33 is a top plan view thereof;
FIG. 34 is a bottom plan view thereof;
FIG. 35 is a perspective view thereof;
FIG. 36 is a front elevational view of a fourth building block of the set of building blocks, shown separately for ease of illustration;
FIG. 37 is a rear elevational view thereof;
FIG. 38 is a left side elevational view thereof;
FIG. 39 is a right side elevational view thereof;
FIG. 40 is a top plan view thereof;
FIG. 41 is a bottom plan view thereof;
FIG. 42 is a perspective view thereof;
FIG. 43 is a front elevational view of a first piece of a fifth building block of the set of building blocks, shown separately for ease of illustration;
FIG. 44 is a rear elevational view thereof;
FIG. 45 is a left side elevational view thereof;
FIG. 46 is a right side elevational view thereof;
FIG. 47 is a top plan view thereof;
FIG. 48 is a bottom plan view thereof;
FIG. 49 is a perspective view thereof;
FIG. 50 is a front elevational view of a second piece of the fifth building block of the set of building blocks, shown separately for ease of illustration;
FIG. 51 is a rear elevational view thereof;
FIG. 52 is a left side elevational view thereof;
FIG. 53 is a right side elevational view thereof;
FIG. 54 is a top plan view thereof;
FIG. 55 is a bottom plan view thereof;
FIG. 56 is a perspective view thereof;
FIG. 57 is a front elevational view of a sixth building block of the set of building blocks, shown separately for ease of illustration;
FIG. 58 is a rear elevational view thereof;
FIG. 59 is a left side elevational view thereof;
FIG. 60 is a right side elevational view thereof;
FIG. 61 is a top plan view thereof;
FIG. 62 is a bottom plan view thereof;
FIG. 63 is a perspective view thereof;
FIG. 64 is a front elevational view of a seventh building block of the set of building blocks, shown separately for ease of illustration;
FIG. 65 is a rear elevational view thereof;
FIG. 66 is a top plan view thereof;
FIG. 67 is a bottom plan view thereof;
FIG. 68 is a right side elevational view thereof;
FIG. 69 is a left side elevational view thereof;
FIG. 70 is a perspective view thereof;
FIG. 71 is a front elevational view of an eighth building block of the set of building blocks, shown separately for ease of illustration;
FIG. 72 is a rear elevational view thereof;
FIG. 73 is a left side elevational view thereof;
FIG. 74 is a right side elevational view thereof;
FIG. 75 is a top plan view thereof;
FIG. 76 is a bottom plan view thereof;
FIG. 77 is a perspective view thereof;

FIG. 78 is a front elevational view of a first piece of a ninth building block of the set of building blocks, shown separately for ease of illustration;
FIG. 79 is a rear elevational view thereof;
FIG. 80 is a left side elevational view thereof;
FIG. 81 is a right side elevational view thereof;
FIG. 82 is a top plan view thereof;
FIG. 83 is a bottom plan view thereof;
FIG. 84 is a perspective view thereof;
FIG. 85 is a front elevational view of a second piece of the ninth building block of the set of building blocks, shown separately for ease of illustration;
FIG. 86 is a rear elevational view thereof;
FIG. 87 is a left side elevational view thereof;
FIG. 88 is a right side elevational view thereof;
FIG. 89 is a top plan view thereof;
FIG. 90 is a bottom plan view thereof;
FIG. 91 is a perspective view thereof;
FIG. 92 is a front elevational view of a first piece of a tenth building block of the set of building blocks, shown separately for ease of illustration;
FIG. 93 is a rear elevational view thereof;
FIG. 94 is a left side elevational view thereof;
FIG. 95 is a right side elevational view thereof;
FIG. 96 is a top plan view thereof;
FIG. 97 is a bottom plan view thereof;
FIG. 98 is a perspective view thereof;
FIG. 99 is a front elevational view of a second piece of the tenth building block of the set of building blocks, shown separately for ease of illustration;
FIG. 100 is a rear elevational view thereof;
FIG. 101 is a left side elevational view thereof;
FIG. 102 is a right side elevational view thereof;
FIG. 103 is a top plan view thereof;
FIG. 104 is a bottom plan view thereof;
FIG. 105 is a perspective view thereof;
FIG. 106 is a front elevational view of a first piece of an eleventh building block of the set of building blocks, shown separately for ease of illustration;
FIG. 107 is a rear elevational view thereof;
FIG. 108 is a left side elevational view thereof;
FIG. 109 is a right side elevational view thereof;
FIG. 110 is a top plan view thereof;
FIG. 111 is a bottom plan view thereof;
FIG. 112 is a perspective view thereof;
FIG. 113 is a front elevational view of a second piece of the eleventh building block of the set of building blocks, shown separately for ease of illustration;
FIG. 114 is a rear elevational view thereof;
FIG. 115 is a left side elevational view thereof;
FIG. 116 is a right side elevational view thereof;
FIG. 117 is a top plan view thereof;
FIG. 118 is a bottom plan view thereof;
FIG. 119 is a perspective view thereof;
FIG. 120 is a front elevational view of a first piece of a twelfth building block of the set of building blocks, shown separately for ease of illustration;
FIG. 121 is a rear elevational view thereof;
FIG. 122 is a left side elevational view thereof;
FIG. 123 is a right side elevational view thereof;
FIG. 124 is a top plan view thereof;
FIG. 125 is a bottom plan view thereof;
FIG. 126 is a perspective view thereof;

FIG. 127 is a front elevational view of a second piece of the twelfth building block of the set of building blocks, shown separately for ease of illustration;

FIG. 128 is a rear elevational view thereof;

FIG. 129 is a left side elevational view thereof;

FIG. 130 is a right side elevational view thereof;

FIG. 131 is a top plan view thereof;

FIG. 132 is a bottom plan view thereof;

FIG. 133 is a perspective view thereof;

FIG. 134 is a front elevational view of a thirteenth building block of the set of building blocks, shown separately for ease of illustration;

FIG. 135 is a rear elevational view thereof;

FIG. 136 is a left side elevational view thereof;

FIG. 137 is a right side elevational view thereof;

FIG. 138 is a top plan view thereof;

FIG. 139 is a bottom plan view thereof; and,

FIG. 140 is a perspective view thereof.

The claimed design is directed to a single set of building blocks, with the individual pieces shown in the drawings forming collective appearance of the design. The broken lines and the faded areas encompassed by the broken lines in the drawings disclose the unclaimed portions of the set of building blocks only and form no part of the claimed design.
